UNITED STATES PATENT OFFICE.

LAWRENCE G. BALDWIN, OF EASTLAND, TEXAS.

COLLAR-BUTTON.

1,382,452.

Specification of Letters Patent. Patented June 21, 1921.

Application filed June 9, 1920. Serial No. 387,680.

To all whom it may concern:

Be it known that I, LAWRENCE G. BALDWIN, a citizen of the United States, residing at Eastland, in the county of Eastland and State of Texas, have invented new and useful Improvements in Collar-Buttons, of which the following is a specification.

The object of the invention is to provide a simple and inexpensive button which may be constructed of nonmetallic material and which being applicable to bands of the usual commercial form will adapt itself to the curvature of the band and afford no objectionable projection or in no way obstruct the free adjustment of the tie in connection with the folded type of collar, and with these objects in view, the invention consists in the construction and combination of parts of which a preferred embodiment is shown in the drawings, wherein:—

Figure 1, is a rear view of a portion of a collar neck band with the collar button arranged in operative relation thereto a portion of the collar being broken away to expose the terminal of the button.

Fig. 2 is a vertical sectional view of the same.

Fig. 3 is a view of the button detached.

The improved button or collar fastener consists essentially of a base or plate 10 which may be formed of any suitable yielding or bendable material having sufficient stiffness to retain its form such as celluloid, card board, or if preferred aluminum or the like, of such dimensions as to permit of its insertion into the pocket ordinarily formed in the back of the shirt collar band or neck band, such pocket usually being provided with its outer wall punctured to form a circular opening or hole to prevent contact of the button engaged therein with the neck of the wearer.

The base or plate 10 is provided with an up-struck or cut-out tongue 11 integral with the base or plate and adapted to be sprung

or deflected from the plane thereof sufficiently, after the introduction of the base unto the pocket of the neck band, to project through the bottom hole for terminal exposure so that the button hole of the collar 50 band may engage therewith. In the construction illustrated, the tongue 11 is separated from the blank forming the base or plate 10 upon a curved line extending around the extremity of the tongue, which when the 55 plate is arranged in the neck band pocket 12 is adapted to project terminally through the neck band button hole 13 so that the collar band 14 having the usual button hole 15 may engage with the said projecting terminal as indicated in Fig. 2 and thus be held in contact with the neck band of the shirt without the objectionable projection ordinarily afforded by the head of a collar button similarly engaged with the registering button holes of the neck band and collar band. The rounded contour of the tongue 11 affords an engaging means by which the sliding movement of a tie fitted between the collar fold 16 and the collar band 14 may 60 be unobstructed and obviously the pressure of the tie will serve to hold the free end of the edge of the tongue members against the collar band and will thus coöperate with the other elements in maintaining the collar 65 in its proper relation with the neck band of the shirt.

The invention having been described, what is claimed as new and useful is:—

A collar button consisting of a flexible 80 plate adapted to conform itself to the shape of a collar where it is attached to the latter, the said button having a base and an integral tongue upstruck from the base and normally lying in the plane of the latter but 85 adapted to be terminally deflected from said plane.

In testimony whereof I affix my signature.

LAWRENCE G. BALDWIN.
